UNITED STATES PATENT OFFICE.

MAXIMILIAN F. BONZANO, OF PHILADELPHIA, PENNSYLVANIA.

MEANS FOR SECURING SPLICE-BARS TO TIES.

No. 923,007.

Specification of Letters Patent.

Patented May 25, 1909.

Application filed October 23, 1908. Serial No. 459,148.

To all whom it may concern:

Be it known that I, MAXIMILIAN F. BONZANO, a citizen of the United States, residing in Philadelphia, Pennsylvania, have invented Improved Means for Securing Splice-Bars to Ties, of which the following is a specification.

My invention relates to track construction; and the object of my invention is to provide fastening means of the type illustrated in my application for patent, filed June 27, 1908, Serial No. 440,702, for use with splice-bars, whereby the latter, together with the rails which they connect, may be securely held to the track and maintained in a fixed position to prevent creeping of the rails. As in my application before referred to, the present device is used in connection with a wear-plate, and it may be employed with wooden or metallic ties.

My invention is fully shown in the accompanying drawings, in which:

Figure 1, is a plan view showing the application of the securing means forming the subject of my invention to the flanges of splice-bars of a well-known type; Fig. 2, is a similar plan view showing splice-bars offset with respect to each other; Fig. 3, illustrates a modified form of construction in which a portion of the flange at one end of each splice-bar is cut away for the application of the retaining means employed at such point directly to the rail flange; Fig. 4, is a sectional view on the line *a—a*, Fig. 1; Fig. 5, is a sectional view on the line *b—b*, Fig. 1, and Fig. 6, is an inverted perspective view of the improved retaining member employed in connection with splice-bars.

In the drawings herewith, 1, 1, represent the meeting ends of the rails which are joined by splice-bars 1^a, 1^a. The splice-bars in the present instance are illustrated as having six bolts and rest upon wear-plates 2 suitably secured to the ties 3; the flanges of said splice-bars being secured to the wear-plate and in proper position with relation to the tie by means of clips 4 held in place by adjusting blocks 5 interposed between the side or end wall of said clips and flanges 6 carried by the wear-plate and, preferably paralleling the rail.

As shown in the several views, the adjusting blocks have inclined edges adjacent to

and for engagement with the clips, and these inclined edges are formed with notches or serrations theréin, as indicated at 7. Such notches or serrations may be disposed at an angle with respect to a vertical plane and engage with similar notches or serrations 8 formed in the clips, or these notches or serrations may be vertical although in most instances their inclination from the vertical is preferable. In addition, the clips may be provided with overhanging lips or flanges 9 which overlie the adjusting blocks 5 and tend to prevent the same rising, and the flanges of the wear plate are preferably undercut, as shown, for the same purpose. The clips are provided with shoulders 10 which abut against the flange of the rail, as shown, and an overhanging portion 11 which rests directly against the top of the flange. In addition, when these clips are employed for direct engagement with the splice bars, they are provided with projections 11^a on the under side arranged to engage the notched or slotted portions of the splice-bar flanges which are nominally employed for spikes. The projection 11^a may be disposed at any point with respect to the clip to engage the notch or slot in the splice-bar; the clips being specially made for such purpose. This construction is for the purpose of anchoring the splice-bars to the ties to prevent the rails creeping.

To secure the clips to the wear plate whereby they may be held against the splice-bar, bolts 12 are provided which extend through apertures 13 in the wear-plate and are secured to the clips by means of nuts 14. Washers 15 are preferably interposed between said nuts and clips, and if desired elastic washers may be placed between the heads of the bolts and the wear plate, or between the bolt heads and the underside of the top web of the tie 16 when the latter is of metal. The wear-plate 2, upon which the rails as well as the flanges of the splice-bars rest, is secured to the tie by bolts 16 having nuts 17, and to make it as well as the rail fastening means adjustable 18 with respect to the tie, washers 18 having elongated flanges of oval or other suitable contour with offset bolt apertures are provided adapted to fit similarly shaped openings provided for the same in said wear-plate. This construction is substantially similar to

that referred to in my pending application noted above, and hence complete description herein is thought to be unnecessary.

In the arrangement of the pair of splice-bars shown in Fig. 1, the clips 4 engage directly with the same, being adjusted by the blocks 5 and retained in place by the bolts 12 and the nuts 14. In this instance, the projection 11^a of each clip engages a spike notch 10 formed in the flange of the splice-bar, as clearly shown in the sectional view, Fig. 4.

In Fig. 2, the splice-bars are shown offset with respect to each other, one clip on each side of each splice-bar engaging the flange of the same at the spike notch, while the other clips, disposed on opposite sides of the joint, abut against the ends of the splice-bars and engage the flange of the rails. In this instance the usual form of adjusting block is 20 employed.

In the structure shown in Fig. 3, the splice bars are positioned as in the structure shown in Fig. 1, with the difference that the base flange of one end of each splice-bar has been 25 removed to permit one clip on each side of the joint to engage the flange of the rail. The web of the splice-bar adjacent the web of the rail has been retained, however, so that the bolts will be disposed in the same manner as 30 in the structure shown in Fig. 1. By providing the clips with projections to engage the spike notches or slots of the splice bar flanges, as well as arranging the clips to abut against the ends of said splice bar flanges, endwise 35 movement of said splice bars with respect to the ties is prevented and creeping of the rail is thereby resisted.

The method of adjusting the splice bar connection to the rails in taking up wear is 40 identical with that indicated in my pending application, and when adjusting the rails and the splice bars securing them, the adjusting blocks may be moved in parallelism, while the clips will be moved at right angles to the 45 rail and the movement of said adjusting blocks, and such movement of said clips is always in this direction; abutting against the rail on the same place. It will be readily understood, therefore, that adjustment may 50 be made by simply lifting the clips 4 and then moving the adjusting blocks the desired distance in the proper direction for the proper engagement of the complementary notches in these parts; the clips being slotted at 22, to 55 permit movement when the adjusting blocks are to be moved with relation thereto. In addition, the wear plates are secured to the tie, and may be adjusted in precisely the same manner as in my application before referred to; thereby giving an additional lateral adjustment for the rails and their splices.

I claim:

1. The combination with a tie of a wear-plate having flanges, splice-bars for securing

together the meeting ends of rails resting on 65 said wear-plate, adjustable retaining members secured to said wear-plate and engaging the flanges of the splice-bars, each of said members having a projection to enter the spike notches of said splice bars, and adjusting blocks coacting with said retaining members and interposed between the latter and the flanges of the wear-plate, said adjusting blocks being held in fixed position with respect to the wear-plate by the means securing 70 the retaining members in place.

2. The combination with a tie, of a wear-plate having flanges, splice-bars for securing together the meeting ends of rails, adjustable retaining members secured to said wear- 80 plate and engaging the flanges of said splice-bars, each of said members having a projection to enter the spike notch of said splice-bar flanges, and a notched or serrated edge 85 on the opposite side, and adjusting blocks having complementary notched or serrated faces interposed between said retaining members and the flanges of the wear-plate, said adjusting blocks being held in fixed position with respect to the wear-plate by the 90 means securing the retaining member in place.

3. The combination of a pair of splice-bars for connecting together the meeting ends of rails, wear-plates carried by the ties 95 upon which said rails and splice bars rest, clips secured to said wear-plates and engaging the flanges of the splice-bars, and adjustable wedges for positioning said clips, the engagement of the latter with the splice-bars 100 serving to anchor the same to the ties and prevent creeping of the rails.

4. The combination of a pair of splice-bars for connecting together the meeting ends of rails, ties, wear-plates carried by said 105 ties, clips secured to said wear-plates and overlying the flanges of the splice-bars, and adjustable wedges for positioning said clips, the latter having projections engaging the spike notches of said splice-bars so as to anchor the same to the ties and prevent creeping 110 of the rails.

5. The combination of a pair of splice-bars for connecting together the meeting ends of rails, wear-plates carried by the ties 115 upon which said rails and splice-bars rest, clips secured to said wear-plates and engaging the flanges of the splice-bars, said splice-bars having flanges offset with respect to each other and one of said clips engaging the end of one of said splice-bars, and adjustable wedges for positioning said clips, the engagement of the latter with the splice-bars serving to anchor the same to the ties and prevent creeping of the rails.

6. The combination of a pair of splice-bars for connecting together the meeting ends of rails, wear-plates carried by the ties

upon which said rails and splice-bars rest, said splice-bars having flanges offset with respect to each other, clips secured to said wear-plates, one of said clips engaging the flange of one of the splice-bars and the other clip abutting against the end of the other splice-bar and engaging the flange of the rail, and adjustable wedges for positioning said clips, the engagement of the latter with

the splice-bars serving to anchor the same 10 to the ties and prevent creeping of the rails.

In testimony whereof, I have signed my name to this specification, in the presence of two subscribing witnesses.

MAXIMILIAN F. BONZANO.
